(57) **CLAIM**

The ornamental design for a blood sugar level measuring device, as shown and described.

DESCRIPTION

FIG. 1 is a top perspective view of a blood sugar level measuring device showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is another perspective view thereof;

FIG. 9 is a top perspective exploded view of a blood sugar level measuring device with a measuring instrument module in dot-dot-dash broken lines provided to illustrate an example environment; and,

FIG. 10 is a top perspective view of a blood sugar level measuring device with a strip for blood-sugar test in dot-dot-dash broken lines provided to illustrate an example environment.

The dash-dash broken lines in FIGS. 1, 2, and 6-10 immediately adjacent to claimed surfaces represent the boundaries of the claimed design and also show portions of the blood sugar level measuring device that form no part of the claimed design. The dot-dot-dash lines in FIG. 9 and FIG. 10 showing the additional measuring instrument module and the strip for an blood-sugar test are for the purpose of illustrating environmental structure and form no part of the claimed design. None of the broken lines form any part of the claimed design.

1 Claim, 8 Drawing Sheets
